SMELTER

Frank G. Shaub and Arthur E. Jennens, Detroit,
Mich., assignors to Ford Motor Company,
Dearborn, Mich., a corporation of Delaware

Application October 24, 1942, Serial No. 463,144

5 Claims. (Cl. 214—30)

This invention relates to furnace construction and operation; and, more particularly, to retort furnaces used in the production of metals.

While the disclosure of this application may be used under different conditions, as a particular example a furnace to be used in the ferrosilicon reduction of magnesium is shown. This is essentially a retort procedure in which the reacting substances are placed in a closed retort, subjected to vacuum or to an inert atmosphere and heated to the reaction temperature, the products of the reaction being segregated by condensation or other means and thereafter removed for further processing. In the example, the reaction constituents are briquettes of a mixture of ferrosilicon and a calcined dolomite. The magnesium formed in the reaction is in vapor form and condenses in a cooler part of the retort from which it is removed in the form of reguline metal. The residue of the reaction consists of the briquettes in which substantial portions of magnesium have been replaced by silicon and which are normally of substantially the shape and size as when they were placed in the retort though they may be slightly softer or may be glazed with a slag depending upon conditions obtaining. This process in general is old and no claim is made to it.

One of the particular difficulties of this operation is the temperatures at which reaction takes place. They are high—well above 2000° F.—and the normal life of a metal retort under these conditions is very short. Further, at the temperatures obtaining, oxidation of both the exterior of the tube within the furnace and the interior of the tube while the same is open and being loaded or unloaded is a serious problem. Another consideration is that preheating of the briquetted charge is sometimes desirable before it is placed in the retort, both to harden the briquettes and to bring them more nearly to the temperature existing in the retort to avoid uneven temperature distribution.

An advantage of this invention is that the furnace design provides a maximum retort capacity and makes full provision for the preheating of the briquette charge. The arrangement shown gives maximum productive capacity as measured against furnace size for a particular furnace building; and, moreover, permits the use of the charging and unloading device, described herein in some detail, to serve a great number of individual furnaces. Another advantage is that charging and unloading time is reduced to a minimum and the over-all productive capacity per

retort increased accordingly. Another advantage is that the thermal efficiency of the system is increased by utilizing what otherwise would be stack heat in the briquette preheating operation. 5 Another advantage is that by the provision of condensing areas at each end of the retort, the length, through which the reaction products must travel before condensation, is shortened accordingly and the tendency toward reversal of the reaction is diminished. Another advantage is the saving in operating labor and avoidance of wear and tear on the retort tube.

With these and other objects in view, the invention consists of the arrangement, construction and combination of the various parts of the improved device, described in the specification, claimed in the claims, illustrated in the accompanying drawings, in which:

Figure 1 is an elevation of a smelter plant employing this invention, portions thereof being shown in section.

Figure 2 is an elevation, on an enlarged scale, of the charger forming a part of this invention.

Figure 3 is a transverse view, on an enlarged scale, through one of the retorts showing the operation of the charger.

Figure 4 is a front view of the furnace shown in Figure 1.

Figure 5 is a view taken as indicated by the line 5—5 of Figure 2, the gear case covers being removed and a portion of the carriage broken away.

Referring to Figure 1, the smelter building is indicated generally as 10 and in it are arranged two opposed banks of furnaces 11, there being a clear central bay 12 between the banks. Mounted in this bay is the overhead crane 13 which carries the charging hopper 14 and the charger 15; both the crane and charger being movable along the bay between the furnace banks. A belt or similar conveyor means 16 is provided to supply the raw materials to the charging hopper.

The furnaces 11 which are preferably gas fired, although they may be of the molten salt type shown in copending application Serial 454,580, include a chamber 17 in which are mounted, in staggered relationship, a number of tubular retorts 18 which have ends 19 extending on the outside of the furnace. Closures 20 are provided for each of the retorts so that they may be tightly sealed and a vacuum connection 21 leads from the interior of the retort to suitable vacuum pumps which are not shown. These retorts are mounted on rollers 22 at various points along their lengths and, so supported, are free for lon-

gitudinal movement caused by thermal expansion.

The furnace also includes an upper preheating chamber 23 heated by the gases leaving the heating chamber 17 through the ducts 24 and exhausting through the stack 25. This preheating chamber has charging ports 26 and a door 27, through which the material in the chamber may be removed. A number of gas jets 28 are provided to heat the interior of the furnace although other conventional heating means may be employed. Dump cars 29 are provided along the front of the furnaces to receive the residue when unloaded for disposal to pits 30.

Attention is now directed to charger 15 which is an essential part of the operation of the installation. It will be noted that the retort tubes 18 are in staggered arrangement, some of them being higher than others, and that their diameters are such that ordinary charging means may not be used. Further, after the reaction, it will be found that the residue which remains is at a white heat and it is difficult to remove this caked mass. Provision must also be made for the transfer of the preheated material from the preheating chamber 23 to the interior of the various retorts. To effect this, the charger includes the central column 35 supporting carriage 36, on which is mounted a peel 37. The central column is secured to table 38 which in turn is rotatably mounted by rollers 39 on a trolley 40. The trolley, as best seen in Figure 2, is rollably mounted in a bridge 41 which in turn runs along the bay 12 on the rails 42.

The carriage 36 is mounted on wheels 43 which run on the central column 35 and a hydraulic plunger 44 secured to the table 38 makes it possible to raise and lower the carriage at will. The carriage also includes, partially as a counter-weight for the peel, an operating platform 45 at which the various controls for operating the charger are centralized. The peel itself comprises a bucket 46 open at the top and secured to the tube 47 which is rotatably mounted in a bearing 48 in the forward part of the carriage 36. A drive motor 49 is operably connected through the coupling 60 to the gear case 50 and the tube 47 to rotate the tube 47 axially, as best shown in Figure 5. This connection includes the pinion 61 keyed to the driveshaft 62 and a meshing gear 63 secured to the extreme rear end of the tube 47 as it projects through the housing 55.

Enclosed within the tube 47 is the pusher 51 which includes an Archimedean screw 52, having at its forward end a breaking knife 53, as shown in Figure 3. Suitable provision is made on the opposite side of the carriage to revolve the pusher axially independently of the movement of the tube 47. This, as shown in Figure 5, includes a motor 49 mounted on the carriage 36 driving a shaft 65 through a coupling 60. A pinion 66 is keyed to the shaft 65 and meshes with the gear 67 slidably mounted on the shaft 54 and restrained from rotation thereon by the spline 65. The pusher 51 has a long rearwardly extending shaft 54 enclosed in the housing 55 and at the rearward end is operably connected to a hydraulic cylinder 56 by means of which the pusher may be advanced or retracted at the will of the operator. It will of course be understood that the axial rotation of the pusher is independent of this longitudinal movement, as is the axial rotation of the tube.

In operation, the briquetted charge is first placed in a preheating chamber 23 through the

ports 26 and brought to the desired temperature. The charger 15 is then brought opposite the doors 27 of the particular chamber by means of a movable bridge 41 and the carriage 36 is raised by means of the hydraulic plunger 44 to the elevation of the preheating chamber floor. During this operation, of course, the trolley 40 is located on the bridge at the far side of the bridge remote from the particular furnace to be charged. The trolley 40 is then moved forwardly and the peel bucket 46 is scooped into the preheated briquette and filled. The trolley is then reversed and the bucket withdrawn, the carriage lowered to the elevation of the retort to be charged and the carriage again advanced moving the bucket into the retort as shown in Figure 1. Forward movement is continued until the bucket is adjacent the rear end of the retort at which point the drive motor 49 is operated and the bucket is revolved axially dumping the load within the retort or the pusher may be advanced to unload the bucket. The bucket is then withdrawn and the same operation is repeated from the preheating chamber until the retort is filled. In the event that the preheating is not utilized, the bucket may be filled directly from the hopper 14. The closures 20 are then applied to the retort and the retorts are evacuated through the connection 21 while the furnace is heated to the desired reaction temperature. When the reaction is completed, the retort is again opened and the magnesium, in regoline form, will be found condensed adjacent the end of the retort. This is removed and the unloading process commenced.

As stated above, the residue which is still largely in briquette form, is a hot glowing mass and may be slightly slagged or coked into a fairly cohesive mass. To remove this, the carriage is brought to the elevation of the retort and the peel is positioned adjacent its mouth as shown in Figure 3. A hydraulic cylinder 56 is then actuated, which advances the pusher 51 into the retort. At the same time, the pusher rotating motor is operated and the pusher screw 52 is given a rotary movement which breaks up the coked mass of residue and propels it rearwardly, as shown in Figure 3, into the disposal car. This operation may be effected at considerable speed, which is important inasmuch as it lessens the period that the interior of the furnace is exposed to oxidation. It will be understood that the retort at this time is still very hot and it is important to minimize the exposure. Another advantage of this particular structure is that the steel bucket may be utilized to some extent to realign the retort which is subject to localized distortion due to the strains imposed by the load and the heat; and there is considerable power available to force the bucket through the retort and restore it to proper alignment.

The operation of one furnace has been described and it is apparent that by rotating the table 38, the same operation may be carried out on the opposite bank of furnaces where, by moving the charger bridge, an entire bank on either side can be serviced at the preheating level and each of the retort levels. However, the operation may be conducted expeditiously so that a minimum of physical equipment is required to maintain a number of retorts in operation.

Some changes may be made in the arrangement, construction and combination of the various parts of the improved device without departing from the spirit of the invention and it is the intention to cover by the claims such changes

as may be reasonably included within the scope thereof.

The invention claimed is:

1. In a smelter charging device, a peel comprising a tube, a bucket at one end of said tube, said tube being mounted for axial rotation, a screw conveyor enclosed within said tube, means to extend said screw conveyor from said tube and means to impart axial rotation to said screw conveyor.

2. In a smelter charging device, a peel, comprising a tube, a bucket mounted on said tube, said tube arranged for axial rotation, a pusher mounted within said tube, means to extend said pusher from said tube, means to impart axial rotation to said pusher, and a screw means formed on said pusher.

3. In a smelter charging means, comprising, a vertical support, a carriage mounted thereon for vertical movement, a peel supported on said carriage, a bucket at the end of said peel, pusher means normally enclosed within said peel, means to extend said pusher means from said peel, means to impart axial rotation to said pusher means, and material screw conveying means associated with said pusher means.

4. In a smelter charging device, comprising, a bridge means arranged for transverse movement with respect to said smelter, a trolley means mounted on said bridge means and arranged for longitudinal movement with respect thereto, a supporting means rotatably mounted on said trolley means, a vertical support on said supporting means, a carriage mounted on said vertical support for vertical motions thereon, a peel carried by said carriage and extending therefrom, a bucket at the end of said peel, a pusher means comprising an Archimedean screw normally within said peel, means to extend said pusher means from said peel, means to impart rotation to said pusher means.

5. In a retort-charging device, a peel means comprising a support for a tube, a tube thereon having a trough at the end remote from said support, a screw means mounted in said tube, means to move said screw means longitudinally with respect to said tube, and means to rotate said screw means with respect to said tube.
